(57) **CLAIM**

The ornamental design for the furniture foot and rail segment, as shown and described.

DESCRIPTION

FIG. 1 is a front elevational view of my new design for a furniture foot and rail segment, showing it incorporated in a chest.

FIG. 2 is a left-side elevational view thereof.

FIG. 3 is a rear elevational view thereof.

FIG. 4 is a right-side elevational view thereof.

FIG. 5 is a top plan view thereof; and,

FIG. 7 is a bottom plan view thereof.

The broken line elements of the chest are for illustrative purposes only and form no part of the claimed design.

FIG. 6

UNITED STATES PATENT AND TRADEMARK OFFICE
CERTIFICATE OF CORRECTION

PATENT NO. : Des. 474,050 S
DATED : May 6, 2003
INVENTOR(S) : Sidney A. Lenger

Page 1 of 1

It is certified that error appears in the above-identified patent and that said Letters Patent is hereby corrected as shown below:

Title page.

Item [63], reads "Division of application No. 29/159,629, filed on April 25, 2002," should read -- Division of co-pending U.S. Design Patent Application Serial No. 29/159,629, filed on April 25, 2002, which is a continuation of U.S. Design Patent Application Serial No. 29/149,641, filed October 12, 2001, now Patent No. D462,540. --

DESCRIPTION, reads "FIG. 7" and should read -- FIG. 6 --.

Signed and Sealed this

Fourth Day of November, 2003

JAMES E. ROGAN
Director of the United States Patent and Trademark Office
